UNITED STATES PATENT OFFICE.

JOHN HENRY SMITH, OF LOS ANGELES, CALIFORNIA.

WAVE-POWER APPARATUS.

SPECIFICATION forming part of Letters Patent No. 768,701, dated August 30, 1904.

Application filed January 13, 1903. Renewed March 12, 1904. Serial No. 197,887. (No model.)

To all whom it may concern:

Be it known that I, JOHN HENRY SMITH, a citizen of the United States, residing at Los Angeles, in the county of Los Angeles and 5 State of California, have invented an Improved Wave-Power Apparatus, of which the following is a full, clear, and exact description.

This invention belongs to that class of wave-power machines in which a weighted float, desirably a vessel partly filled with water, is made to rotate a wheel or pulley by means of 10 a vertical connection attached to a ratchet-clutch.

An object of this invention is to provide an 15 extremely simple, durable, and compact apparatus.

Another object is to provide an apparatus which may be quickly and easily adjusted to the different states of the body of water upon 20 which it is used, thereby to at all times utilize approximately the entire lifting force which the waves exert upon the floats and yet be protected from injury by storms.

A further object is to provide means which 25 will admit of the free rise and fall of the floats, but will at the same time secure said floats from being swept out of place by the force of the waves during a storm.

Another object is to provide a device in 30 which the power may be transmitted at a comparatively high speed from the driving means, thus making it unnecessary to employ any considerable amount of gearing.

With these and other objects in view my 35 improved apparatus consists in a series of co-operating wave-power devices each comprising a rotatable wheel, preferably about thirty feet in diameter, vertically mounted upon a suitable wharf or pier, each wheel being provided, with a quick-acting ratchet-clutch, a suitable gearing, a weighted float, and a suitable connection leading from said float to the ratchet-clutch.

This invention also consists in the separate 45 devices, combinations, and details of construction, which will be more fully described in connection with the accompanying drawings, in which—

Figure I is a side elevation of one of the 50 wave-power devices constructed in accordance

with my invention. Fig. II is a plan of Fig. I. Fig. III is a diagram, on a reduced scale, of an entire apparatus embodying my invention. Fig. IV is an end elevation of one of the wave-power devices. Figs. V and VI are sections 55 of the ratchet-clutch taken, respectively, on lines V V and VI VI of Fig. VII. Fig. VII is a fragmental mid-section of a driving-wheel, showing the hub thereof with one of the ratchet-clutches operatively connected therewith. 60

Upon a suitable pier 1 is mounted a series of independent wave-power devices 2. Said devices each includes a stationary shaft or axle 3, upon which is mounted a hub or revolvable part 4, furnished with a metal extension 5, having an inner periphery provided with teeth 6.

7 designates a spring - returned ratchet-clutch furnished with a connection 8, partially 70 coiled therearound. Said connection leads to a yoke 9, which is attached by a pin 10 to a bar 11. Said bar is provided with a series of holes 12.

13 is a clevis adapted to be fastened to the 75 yoke 9 by the pin 10, or the clevis may be adjustably fastened to said bar by means of an additional pin 14, inserted through the holes 12.

15 is a lower connection and leads from the 80 clevis 13 to a weighted float 16.

The ratchet-clutch 7 is provided with a collar *a*, keyed to the stationary shaft 3 and having the inner end of a spiral spring *b* attached thereto at *c*. The outer end of said spring is 85 attached at *d* to the inside of a hollow pulley *e*, which is fixed to a base *f*, being rotatably mounted together therewith on the stationary shaft 3. To said base *f* is attached a dog-holder *g* by screws *h*, one at each end thereof. 90 Said screws *h* form pivots for oppositely-disposed dogs or pawls *i*, *j*. Means are provided for swinging said dogs simultaneously outward into engagement with the teeth 6. Said means includes a dog-shift *k*, formed in two 95 parts *m*, *n* and caused to frictionally embrace the stationary shaft 3 by means of tension-springs *o*, mounted on screws *p*. Each dog is pivotally connected with the adjacent end of the dog-shift by means of a shift-pin *q*. 100

At the beginning of the downward movement of the float 16 the clutch-operating connection 8 will begin to rotate the hollow pulley *e* and the base *f*, fixed thereto, against the resistance of the spiral spring *b*. This movement will tend to rotate the dog-shift *k* upon the stationary shaft 3. Since said dog-shift frictionally engages the shaft, it will at first remain stationary thereon and will therefore move relatively to the rotating dog-holder *g*, thus causing the shift-pins *g* to swing the dogs *i*, *j* outward into engagement with the teeth 6 of the metal toothed extension 5. As soon as the dogs begin to engage said teeth the dog-shift *k* will be compelled to rotate upon the shaft 3 until the float 16 reaches the end of its downward movement. When said float begins to rise, the spiral spring *b* takes up the slack in the clutch-operating connection 8, and the dogs are withdrawn from engagement with the teeth by a movement the reverse of that just described.

17 designates a safety-stop limiting the downward movement of the bar 11 to prevent the weight of the float from extending the spiral spring *b* so far as to injure it.

A pair of unequal driving-pulleys 18 19 is provided for each wave-power device, the smaller pulley, 18, to be used in heavy weather, the larger one, 19, being provided for calm seas. Further adaptation to the state of the sea is to be secured by suspending the float at various points along the length of bar 11 by means of clevis 13 and pin 14, inserted through holes 12. A series of driven pulleys 20, arranged in pairs along the revoluble shaft 21, are provided to be connected with pulleys 18 or 19 by means of suitable belts 22.

23 designates a gear-pulley whereby the power may be transmitted, through a belt 24, to a dynamo 25, from which electrical energy may be conveyed by wires *w*.

The driving-pulleys 18 19 may be made very large as compared with the driven pulleys 20. Since said driving-pulleys are fixed one to each side of the fly-wheel, a compact rotary frame is thereby formed which is well adapted to stand the severe strains put upon the wave-power machinery. This arrangement also secures a high speed without making the driven pulleys unduly small or resorting to an extended train of gearing.

For clearness of illustration in Fig. V the ratchet-teeth are made few in number as compared with what will be necessary in the size of clutch used in actual practice.

What I claim, and desire to secure by Letters Patent of the United States, is—

1. In a wave-power, in combination, a wheel, a ratchet-clutch therefor, a return for said clutch, a weighted float, and means independent of the clutch, limiting the downward movement of the float.

2. In a wave-power, in combination, a wheel, a ratchet-clutch therefor, a spring-re-

turn for said clutch, a weighted float, and means independent of the clutch limiting the downward movement of the float.

3. In a wave-power, in combination, a wheel, a ratchet-clutch therefor, a return for said clutch, a weighted float, means operatively connecting the clutch and float, a safety-stop, and means adapted to engage said stop to limit the downward movement of the float.

4. In a wave-power, in combination, a wheel, a ratchet-clutch therefor, a return for said clutch, a weighted float, a safety-stop, and a pivoted bar adapted to engage said stop to limit the downward movement of the float.

5. In a wave-power, in combination, a wheel, a ratchet-clutch therefor, a spring-return for said clutch, a weighted float, means operatively connecting the clutch and float, a safety-stop, and a pivoted bar adapted to engage said stop to limit the downward movement of the float.

6. In a wave-power, in combination, a wheel, a ratchet-clutch therefor, a spring-return for said clutch, a weighted float, a connection between the clutch and the float, a pivoted bar, means adjustable lengthwise the bar for attaching the bar to the connection, and a stop limiting the downward movement of the bar.

7. In a wave-power, in combination, a pier, a wheel mounted thereon, a ratchet-clutch for said wheel, a spring for returning said clutch, a pivoted bar, a stop limiting the downward movement thereof, a yoke mounted on said bar, a connection between said yoke and clutch, a float, and means adapted to suspend the float from the yoke.

8. In a wave-power, in combination, a pier, a pulley mounted thereon, a toothed hub rigidly connected with said pulley, a ratchet-clutch for said hub, a spring for returning said clutch, a pivoted bar, a stop limiting the downward movement of said bar, a yoke mounted on said bar, a connection between said yoke and clutch, a clevis adapted to be attached to the yoke, means for adjustably attaching the clevis to the bar independently of the yoke, a float, and a connection between the float and the clevis.

9. In a wave-power, in combination, a pier, a stationary shaft supported thereby, a pulley rotatably mounted on said shaft, a part having a toothed inner periphery and fixed to said pulley to rotate therewith on said shaft, a collar fixed to said shaft, a member having a limited rotation on said shaft and adapted to act as a driven pulley, a resilient connection between said member and said collar tending to return the member to its normal position, a pair of oppositely-disposed dogs carried by said member, means for simultaneously throwing said dogs into engagement with the toothed inner periphery of the aforementioned part, a pivoted bar, a stop limiting the downward movement thereof, a yoke mounted on said bar, a

connection fastened to the yoke and having an end fastened to and coiled upon the aforementioned member, a clevis adapted to be attached to the yoke, means for adjustably attaching the 5 clevis to the bar independently of the yoke, a float, and a connection between the float and the clevis.

10. In a wave-power, in combination, a suitable pier, a stationary axle, a fly-wheel rotatably mounted thereon, a pulley fixed to one side of said fly-wheel and having a periphery concentric with the fly-wheel and adjacent to the periphery thereof, a pulley of smaller diameter than the first-named pulley and fastened to the other side of the fly-wheel concentric therewith, a hub for the fly-wheel, said hub provided with ratchet-teeth, a spring-returned ratchet-clutch operatively connected with the ratchet-teeth of the hub, a weighted 15 float, a flexible connection leading therefrom to the ratchet-clutch, and means for keeping the float in place.

11. In a wave-power, in combination, a suitable pier, a stationary axle mounted thereon, 25 a fly-wheel rotatably mounted on said axle, a pulley fixed to rotate with said fly-wheel on one side thereof, another pulley of smaller diameter than the first-named pulley and rotating with the fly-wheel at the other side thereof, a hub on each side of the fly-wheel, said hub provided with ratchet-teeth, a spring-returned ratchet-clutch operatively connected with the ratchet-teeth of each hub, a pair of weighted floats, power-transmitting means 35 connecting each float to the ratchet-clutch on that side of the fly-wheel, and means for keeping said floats in place.

12. In a wave-power, in combination, a suitable pier, a stationary axle supported thereby, 40 a fly-wheel rotatably mounted on said axle, a pulley fixed to one side of the fly-wheel, a metal extension fixed to said fly-wheel on the same side as the pulley and provided with a toothed inner periphery, a spring-returned 45 ratchet-clutch fastened to the axle and having a pair of oppositely-disposed pawls in operative connection with the teeth in the exten-

sion, a weighted float, and a connection leading therefrom to the ratchet-clutch whereby said clutch is rotated when the float fails. 50

13. In a wave-power, in combination, a suitable pier, a stationary axle supported thereby, a fly-wheel rotatably mounted on said axle, means moving with the fly-wheel to transmit power therefrom, a metal extension fixed to 55 the hub of said fly-wheel and provided with a toothed inner periphery, a weighted float, a connection therefor, a ratchet-clutch having a collar keyed to the axle and a part movable with relation to the axle, a spring connection 60 between the movable part and the collar, a pair of oppositely-disposed pawls mounted on the movable part, and means simultaneously swinging said pawls outward into engagement with the teeth of the extension at the begin- 65 ning of the fall of the float.

14. In a wave-power, in combination, a pier, a stationary axle supported thereby, a wheel rotatably mounted on said axle, a metal extension fixed to the hub of said wheel and 70 provided with a toothed inner periphery, a weighted float, a power-transmitting connection therefor, a set of piles embracing said float to keep it in place, a ratchet-clutch having a collar keyed to the aforementioned axle, 75 and a part movable with relation to said axle, a resilient connection between the movable part and the collar and tending to resist their relative rotation, a pair of oppositely-disposed dogs mounted on the movable part, and means 80 simultaneously throwing said dogs into engagement with the teeth of the hub at the beginning of the fall of the float.

In testimony whereof I have signed my name to this specification, in the presence of three 85 subscribing witnesses, at Los Angeles, in the county of Los Angeles and State of California, this 7th day of January, 1903.

JOHN HENRY SMITH.
